Primary Examiner — T. Chase Nelson(74) *Attorney, Agent, or Firm* — Andrew F. Young, Esq.; Lackenbach Siegel, LLP(57) **CLAIM**

The ornamental design for a shoe sole, as shown and described.

DESCRIPTION

FIG. 1 is a top front side perspective view of the embodiment of the present invention.

FIG. 2 is a front elevation view of the embodiment shown in FIG. 1.

FIG. 3 is a rear elevation view of the embodiment shown in FIG. 1.

FIG. 4 is a top plan view of FIG. 1.

FIG. 5 is a bottom plan view of FIG. 1.

FIG. 6 is a left side elevation view of the embodiment shown in FIG. 1; and,

FIG. 7 is a right side elevation view of the embodiment shown in FIG. 1.

No claim is made to the dashed line regions on the shoe sole, including the inner diamond tread-region and the shoe upper portions shown as the dashed lines. Dashed lines indicate disclaimed portions forming no part of the claimed design, and the break-lines (dash-dot-dash) indicate the boundaries of the claimed portions. No claim is made to the top portion or side portions of the shoe, other than in claimed-lining in any of the figures, and this is shown as an environmental illustration only to aid the public.
